UNITED STATES PATENT OFFICE.

JESSE H. MAXWELL, OF BARBOURSVILLE, WEST VIRGINIA, ASSIGNOR OF ONE-HALF
TO STEPHEN G. JOHNSTON, OF BARBOURSVILLE, WEST VIRGINIA.

CAR-BRAKE.

1,158,705.

Specification of Letters Patent.

Patented Nov. 2, 1915.

Application filed October 7, 1914. Serial No. 865,538.

To all whom it may concern:

Be it known that I, JESSE H. MAXWELL, a citizen of the United States, residing at Barboursville, in the county of Cabell and 5 State of West Virginia, have invented new and useful Improvements in Car-Brakes, of which the following is a specification.

This invention relates to railway car brakes and has for its primary object the 10 provision of a structure whereby the car can be held at a stand still independent of the air brake system.

Another object of my invention is the 15 provision of a structure wherein the parts can be readily detached from the car when in its assembled form and readily attached to another car.

A further object of the invention is the 20 provision of a structure wherein the shoe has a limited downward play so as to be in position to engage the surface of the rail when the handle is being detachably applied to the sill of a car.

The invention, consists in the features of 25 construction, combination, and arrangement of parts, hereinafter fully described and claimed, reference being had to the accompanying drawing, in which:

Figure 1 is a longitudinal section through 30 a car truck showing the brake in applied position. Fig. 2 is a perspective view of the brake. Fig. 3 is a detail view showing the parts disassembled. Fig. 4 is an end view of a car showing my device applied 35 thereto.

Referring to the drawings, the numeral 1 designates the sill of a car which has in 40 its end an aperture 2 adapted to receive the offset end 3 of the lever 4 of my break mechanism. Rigidly secured to the handle just above the offset end 3 is the bent extremities 5 and 6 of connecting members 7 and 8. The free extremities of the connecting members 7 and 8 are provided with 45 elongated openings 9 and 10 adapted to loosely receive the headed ends 11 and 12 of bolts 13. The opposite ends of the bolts are threaded to receive binding nuts 14 for securing therebetween a transverse shoe 15 50 adapted to span the distance between the opposite rails. That surface of the shoe which comes into contact with the treads of the wheels is shaped so as to conform to the outline of the wheel so that when the

shoe is positioned between the wheel and 55 the rail, excessive friction is created which prevents movement of the car.

It is noted that the offset end 3 is detachably connected in the apertures so that the brake can be removed when necessary. 60 The upper and lower walls of the elongated openings 9 and 10 will contact with the surfaces of the bolt when the latter are moved out of their horizontal position, thus limiting the downward movement of the 65 shoe so that the latter will always be in a position with relation to the tread surfaces of the rails to be slid under the wheels when the lever is moved in a direction away from the body of the car. 70

From the foregoing description taken in connection with the accompanying drawings, the advantages of the construction and of the method of operation will be readily apparent to those skilled in the art to which 75 the invention relates, and while I have described the principle of operation of the invention, together with the device which I now consider to be the best embodiment thereof, I desire to have it understood that 80 the device shown is merely illustrative and that such changes may be made when desired as are within the scope of the claims.

What is claimed is:

1. A brake for a car comprising in combination with the sill of a car having an aperture therein, a lever having a portion 85 slideable in said aperture, a shoe, and means interposed between said shoe and lever whereby the former may be thrown into contact 90 with the tread surface of the car wheels.

2. A brake for a car comprising in combination with the sill of a car having an aperture therein, a lever having a hook portion 95 detachably engaging the walls of the apertures, a shoe, and means interposed between said shoe and lever whereby the former may be thrown into contact with the tread surfaces of the car wheels, said means including bolts having their adjacent ends 100 loosely mounted in said lever.

In testimony whereof I affix my signature in presence of two witnesses.

JESSE H. MAXWELL.

Witnesses:

H. S. KING,
M. C. JOHNSON.
